SLIDE BRACKET FOR PLAYGROUND APPARATUS HAND RING

Isadore Horowitz, Shreveport, La.

Application June 11, 1954, Serial No. 30,938

Term of patent 14 years

(Cl. D54—2)

Fig. 1.

Fig. 2.

Fig. 3.

Fig. 4.

Fig. 1 is a side elevational view of a slide bracket for playground apparatus hand ring, showing my new design;

Fig. 2 is a top plan view thereof;

Fig. 3 is a bottom plan view; and

Fig. 4 is an end elevational view looking at the left of Fig. 1.

I claim:

The ornamental design for a slide bracket for playground apparatus hand ring, as shown.
